HARVEY D. WILLIAMS, OF NEW YORK, N. Y., ASSIGNOR TO THE WATERBURY TOOL COMPANY, OF WATERBURY, CONNECTICUT.

POWER GENERATING AND TRANSMITTING MACHINERY.

1,198,093.

Specification of Letters Patent. Patented Sept. 12, 1916.

Application filed September 21, 1911. Serial No. 650,554.

To all whom it may concern:

Be it known that I, HARVEY D. WILLIAMS, a citizen of the United States, and resident of the borough of Manhattan, city, county, 5 and State of New York, have invented certain Improvements in Power Generating and Transmitting Machinery, of which the following is a specification.

My invention relates to power plants of 10 the type commonly used for propelling automobiles and motor boats wherein the power developed by an internal combustion engine is transmitted through a speed changing and reversing mechanism to a propeller shaft or 15 its equivalent. For the transmission I use a variable speed gear of the type in which a liquid (preferably lubricating oil) circulates through a pump and a motor, the volumetric rigidity of the liquid imparting a quality of 20 positiveness to the transmission, and in which an infinite series of speeds is obtained by varying the stroke of the pump. In my improvement I combine the pump-half of 25 the variable speed gear with the internal combustion engine thus making a pumping engine which, in addition to its being more compact and of less weight, is also more efficient as an engine and less complicated as 30 a pump than are the corresponding parts which my improvement is designed to replace.

The simplest type of general arrangement of my invention is shown in Figure 1 in which 1 is the pumping engine, 2 is the motor-half of the variable speed gear, 3 is the propeller shaft, 4 and 5 are the circulating pipes for the fluid connection between the pump and the motor, 6 is a combined safety and reversing valve, and 7 is a combined replenishing and back pressure pump. The motor 2 is any hydraulic motor working by fluid pressure and imparting a motion which is reversed by reversing the direction of circulation through the pipes 4 and 5. Fig. 2 40 is a section of the pumping engine at right angles to the crank shaft in the plane of a cylinder axis and looking as indicated at A. Fig. 1. Fig. 3 is a parallel section in a plane midway between two cylinder axes as indicated at B Fig. 1. Fig. 4 is a section through three adjacent cylinder axes looking as indicated at C Fig. 2. Fig. 5 is a partial plan view of the pumping engine showing four adjacent cylinders the walls of which are 50 cut as indicated at D Fig. 2. Fig. 6 is a sec-

tion parallel to Fig. 4 in the plane of the axes of the pump cylinders as indicated at E Fig. 2 but with certain moving parts in different positions. Fig. 7 is a detail plan view, partly in section, showing chiefly the pump 60 plunger and parts connected therewith; Figs. 8, 9, 10, and 11 are vertical sections of a combined safety and reversing valve and its casing, showing the valve in four different positions, Fig. 9 also illustrating the 65 mechanism for shifting said valve; Fig. 12 is a central vertical section through the pump, looking as indicated at F in Fig. 1; Fig. 13 is a vertical section of a modification, said view being taken on a plane corresponding to Fig. 2; Fig. 14 illustrates said modification by a sectional view corresponding to Fig. 12; Figs. 15 and 16 are vertical sections of the safety valve and its casing 70 employed in this modification, showing the 75 said valve in two different positions; Fig. 17 is an elevation of an arrangement embodying my invention, which dispenses with a separate reversing valve, and in which the driving shaft and the driven shaft are 80 aligned and may be coupled for a direct drive; Fig. 18 is an elevation of another form of my invention in which the engine and motor shaft are geared together.

Referring to Figs. 2, 3, and 4, the engine 85 cylinder 8, driving member or piston 9, piston pin 10, and connecting rod 11, differ in no essential respect from the parts commonly used in engines of this type. The same is true of the engine valve gear and 90 other parts which are for that reason omitted from the drawings and only those parts shown which relate to the present invention. Thus the crank shaft 12 has five cranks (or some other odd number) equally 95 spaced around the circumference of the crank circle whereas common practice favors the 180° spacing of an even number. The reason for this difference is that in my invention the determining factor is the importance that the pump delivery shall be as free as possible from pulsations and it being well known that that quality is characteristic of the first arrangement of cranks noted above. With five cranks (supposed 100 numbered in their order along the shaft) the best order of sequence in the revolution is 1st, 3rd, 5th, 2nd, 4th. This gives a favorable balance of the inertia forces of all moving parts including the new group which I 110

have added in the process of converting the simple engine into a pumping engine. The aggregate group associated with each crank is the same for all, so that a description of one will suffice. The connection between the new pump group and the old engine group occurs at the piston pin 10. Engaging with this pin on either side of the engine connecting rod is a pump connecting rod 13 the forked lower ends of which engage by the pins 14 with the lever 15 the shape of which is better understood by reference to Fig. 7. Fixed to the lever 15 is the pin 16 which engages with the pump plunger 17. Pump plunger 17 is constrained to move in a vertical line by the bore of pump cylinder 18 Fig. 6 assisted by the two upward prolongations 19 of the cylinder walls, said prolongations being so disposed as to most effectually resist the horizontal components of forces acting on the lever 15. On each side of lever 15 there is a rectangular channel in which slides a block 20. Blocks 20 turn on the pins 21 which are carried by the brackets 22 which have a sliding connection with the stationary part 8. The constraints of the sliding connection between the last named parts consist of the flat contact between brackets 22 and the under side of 8, a tongue on 22 engaging with a slot in 8 and the flat contact between the plate 23 (secured to 22) and the upper side of 8.

Referring to Fig. 5 it is seen that a single plate 23 is secured to the several brackets 22 by the screws 24. The use of a single plate 23 insures the exact alinement at all times of the several pins 21 and facilitates the simultaneous and parallel movement of the said pins in a horizontal direction. To insure the parallelism of this movement I use a parallel motion consisting of two equal bell cranks 25, two equal connecting rods 26, and one long connecting rod 27; said parts being pivoted together in the order shown and the distance between the pair of pivots carried by the parts 8, 23 and 27 being equal. An arm of one bell crank is slightly prolonged and carries a manual control handle 28. Thus at will may the pins 21 be moved to and fro horizontally from the position shown in Fig. 3 through the position shown in Fig. 2 to an extreme position (not shown) determined in this case by the contact of bracket 22 with the casing at 88. In Fig. 3 and Fig. 6 the pins 21 are in alinement with the pins 16, the pump plungers are held immovable and the turning over of the engine results merely in a rocking movement of lever 15 about the fixed center of pin 16. With the movement of pins 21 away from the position shown in Fig. 3 the pump stroke is gradually increased from zero to a maximum the stroke being in fact proportional to the displacement of the pin

21. By aid of the linkwork here disclosed it is evidently possible from a moderate pressure in the engine cylinder to develop a pressure under the pump plunger all the way from moderate to very great, the pressure being in fact inversely proportional to the displacement of the pin 21. 70

An important feature of my invention will be brought out by a comparison of the conditions affecting the efficiency of power 75 transmission from the engine piston to the pump cylinder and to the crank shaft respectively.

In the pump link work the joint pins are small in diameter and the angular movements are small compared to that of the crank shaft. At the piston pin the movement is especially small and the correspondingly slight angularity of the pump connecting rod signifies very little side pressure and 80 consequent friction between engine piston and cylinder. Also as influencing side pressure the method employed for reciprocating the pump plunger is especially favorable. Thus the mean value of the side pressure between the pump plunger and the cylinder wall due to the angularity of the lever 15 is about one half what it would be if the plunger were driven from a crank through a connecting rod having a maximum angularity equal to that of the lever 15. Besides which the pump plunger, by virtue of its pumping oil, is ideally lubricated. The transmission of power being equally divided among the several pump linkworks it follows that no part of any linkwork need be stronger than necessary to do the work of one pump. On the other hand we have in the engine linkwork (before the pumps were added) two turning joints (crank pin and main bearing) each with an angular movement of a complete revolution and 90 large enough in diameter to transmit the combined power of the several engine cylinders, together with a connecting rod of large angularity and proportionate side pressure between piston and cylinder wall where the conditions for lubrication are not the best. 95

After the pumps are added according to my invention the principal function of the crank shaft is to preserve the time sequence of the several pump strokes. Especially is this the case if we suppose the engine to be of the two cycle type since here, with each downward stroke a working stroke, and with each associated pump taking just the amount of energy developed in the engine, it is evident that comparatively little stress will be thrown on the crank shaft, a circumstance which permits of lighter construction and consequent further increase of efficiency. 110

The pump draws its supply of oil from the duct 29 by way of the check valve 30 and discharges through the check valve 31 115

into the duct 32. For purposes of illustration check valves 30 and 31 are represented as being guided on a small tension rod 75 and held against their seats by light helical springs. In actual construction I use a type of check valve better adapted for high speeds but not easily shown in one view. The ducts 29 and 32, extending the whole length of the engine frame, are closed at the ends and communicate by the flanged connections 33 and 34 respectively with the interior of the safety and reversing valve 6. From the disposition of the check valves 30 and 31 it is evident that the highest occurring pressure will always be in duct 32 and connection 34.

The combined safety and reversing valve comprises a valve body 35 Fig. 8 having four interior annular ports, two of which communicate upward with the flanged connections 33 and 34 already noted and the alternate two communicate downward with the similar connections 4 and 5 and through them with the like numbered circulating pipes shown in Fig. 1. The valve proper 36 is a balanced piston valve with a central longitudinal opening and an outside circumferential channel of width sufficient to span two adjacent ports in the valve body. The valve 36 is moved by the valve stem 37 which passes out through the stuffing box 38. Mounted on the outer end of the valve stem is the spring box 39, the spring 40 and the plug 41 the latter screw threaded into the end of the spring box and having a squared end for turning to adjust the tension on the spring. The other end of the spring bears against collar 42 on the valve stem which in turn bears against the spring box so that the force of the spring acts to hold the valve stem and the spring box in the relative position shown in Fig. 8.

Regarded as a reversing valve the two normal positions—one for going ahead and one for backing—are shown in Fig. 8 and Fig. 10 respectively. In Fig. 8 port 34 is in communication with port 5 and port 33 with port 4. In Fig. 10 these relations are reversed, 34 being in communication with 4 and 33 with 5. For shifting the valve for reversing and for holding it in either of the normal positions I provide the manual control handle 43 Fig. 9 which is pivoted to the stationary frame at 44 and carries at its lower end the pin 45 which engages between the two collars 46 on the outside of spring box 39.

The functioning of the valve as a safety valve for the relief of excessive pressure when going ahead is shown in Fig. 9. As already noted the highest occurring pressure is always in the connection 34 which is in free communication through the center of the valve with that end of the casing where the valve stem 37 passes out through

the stuffing box 38. The force due the high pressure acting on the cross section area of the valve stem is therefore unbalanced within the valve body and tries to push the valve stem outward against the spring 40. Whenever a certain pressure (determined by the arbitrary setting of spring 40) is exceeded the spring yields and permits the valve to move from the Fig. 8 position to the Fig. 9 position thus automatically relieving the excessive pressure by providing a by-pass since in Fig. 9 all four ports are in free communication with each other as a result of the valve lands having been made narrower than the valve ports. In like manner an excessive pressure while backing is automatically relieved by the movement of the valve from the Fig. 10 position to the Fig. 11 position.

By means of a plurality of pumps of the kind disclosed acting in concert under the timing control of a single crank shaft it is evidently possible, under conditions of constant revolutions of the crank shaft, to produce a fairly steady flow through the fluid passages 4 and 5 and the motor 2, the velocity of flow and the revolutions of the motor being variable at will between zero and a maximum; and by aid of the reversing valve the said flow and revolutions can be immediately reversed from any value, plus or minus, to the corresponding value of the opposite sign. In order however, to prevent the possible stalling of the engine by the inertia of a too sudden reversal (as for example when the motor is geared to a drawbridge) I provide a means which may be used for interlocking the two manual control handles 28 and 43 (for changing the speed and for reversing respectively) so that reversal can be attempted only when the speed is zero. One of the brackets 22 (the one lying in the plane of the central position of the control handle 43) has a projection 47 long enough to obstruct the movement of handle 43 Fig. 9 except when bracket 22 is in the zero position Fig. 3 as regards stroke of pump and speed of motor. With this arrangement it is evidently impossible to shift the reversing lever without having first moved the speed control handle to the zero position. Variable speed gears of this type require some insurance against loss (by leakage) of the integrity of the fluid connection. In the present case this insurance consists of means for collecting leakage and an auxiliary pump adapted to return to the fluid connection such leakage. Thus oil leaking from the fluid connections through the working joints at the motor end of the speed gear is conveyed by the pipe 48 Fig. 1 to the pocket 49 Fig. 3 which catches also any leakage from the working joints of the pump. The only leakage from high pres-

sure working joints not thus accounted for is the very small amount from the valve stem stuffing box 38. Hence, so far as the mere replenishment of leakage is concerned it would be sufficient to pipe the oil direct from pocket 49 to the low pressure duct 29. It is desirable however to maintain throughout the fluid connections pressures higher than atmospheric. In no other way (except by immersing everything in oil) can the sucking of air be prevented not only at the working joints but often also at permanent joints as well. Even if the sucking of air is prevented by immersion in oil still the maximum speed at which the machine can be run is apt to be determined by the production at points of lowest pressure in the circulatory passages of voids or partial vacuums the result of a too close approach to zero absolute pressure. For maintaining a pressure higher than atmospheric in the low pressure duct and for returning to said duct and against said pressure the oil that has leaked past the working joints of the speed gear I use the combined replenishing and back pressure pump, 7. The eccentric 50 Fig. 12 is keyed to the engine crank shaft 12 and the drain pipe 51 is in communication with the pocket 49. The stationary part or frame of the pump is built in the form of a box 52 to serve as a storage reservoir and so that all working joints of the pump may be immersed and so that joints of whatever kind which are subjected to less than atmospheric pressure cannot in any case leak air but only oil. The plunger 53, the connection from the plunger to the eccentric 50, the suction and discharge check valves 54 and 55 are without novelty in construction or operation. In a cylindrical recess however in the lower part of box 52 there is a sliding piston 56 arranged to vacillate between the force of spring 57 on one side and the discharge pressure of the pump on the other. Under an excess of the latter the piston 56 moves to the right against the spring and shuts off at 58 the access of oil to the suction valve 54. Otherwise there is free access from the tank space 59 to the suction valve through the hole 59 and the holes in the spring adjusting nut 60. The nut 60 is rotated to adjust the spring tension by means of the square rod 61 which engages by ground joint with the plug 62 and is accessible on the outside of the tank. The final discharge of the pump is through the opening 63 right into the low pressure duct 29. In order to operate as intended the capacity of the pump working continuously at full stroke must be enough to more than take care of the maximum amount of leakage from all parts of the variable speed gear. Such being the case it is evident that, with the construction shown, the pump working continuously can-

not fail to maintain in the low pressure duct the pressure for which the spring 57 is set. Nor can the pump exceed that pressure much less create an excessive pressure owing to the manner in which the pump is governed by throttling its suction. Voids will of course be created in the suction passages during each suction stroke of the pump but these voids will close up and disappear during the next compression stroke since there is no opportunity for access to the voids of anything but oil and its vapor.

Figs. 13, 14, 15 and 16 show certain changes which follow more or less imperatively from an important though inconspicuous alternative construction of the link-work in Fig. 13. The alternative consists in permitting pin 21 to assume a position between pins 14 and 16. In other words the movement of bracket 22 to the left carries pin 21 beyond pin 16 instead of only to pin 16 as heretofore. The advantage of this construction is that it permits of the elimination of the reversing valve by arranging all speeds, forward and reverse, in a single series coordinate with a corresponding series of positions of a single control lever. In order to derive this advantage however, it is necessary to replace the check (fluid operated) valves of Fig. 2 with a positively operated valve such as 64 Fig. 13. Here we have a balanced piston valve with a middle land wide enough to cover the cylinder port 65 and having a central longitudinal opening to prevent the blind pocket at the right hand end of the valve from interfering with its freedom of movement. The valve is reciprocated by a connecting rod and an eccentric whose shaft, through chain gearing 66, is driven from the engine crank shaft at the same speed as the latter and in the same direction. From general principles of valve setting we know that the valve must be at mid stroke (in the act of closing one port and opening another) when the pump plunger is at the end of its stroke, a condition which is realized in this particular case by setting the eccentric radius parallel to the engine crank radius.

In operation suppose the crank to be on the lower dead center and turning in the direction indicated by arrow 67. The engine piston is about to begin an upward stroke, hence the pump plunger is about to begin a downward or pressure stroke and has just finished an upward or suction stroke. Valve 64 is moving to the right. It has just closed a passage between 65 and duct 69 which, having been in communication with the pump cylinder during a suction stroke, is therefore the low pressure duct. Also valve 64 is about to open a passage from 65 to 68 which is therefore the high pressure duct.

If pin 21 is supposed moved to the right to some position such that pin 16 lies be-

tween pins 14 and 21 then, reasoning as in the last paragraph, pump plunger 17 will have just finished a pressure stroke. Valve 64 has just closed a passage from 65 to 69. 5 Hence 69 is the high pressure duct, and 68, with which communication is about to be opened, is therefore the low pressure duct. The functions of ducts 68 and 69 have been reversed by the supposed movement of pin 21. It is clear that reversal takes place whenever fulcrum 21 passes the center of pin 16. Hence changes of speed and reversal are both accomplished by the one handle 28 and there is no need of a special 10 reversing valve.

As regards the relation between the several groups of linkwork it only needs to be said that the piston valves are all driven from one eccentric shaft and the sequence 20 of the eccentrics is the same as the sequence of the cranks, the radius of each eccentric being parallel to the radius of the associated crank. The possibility of driving the eccentric shaft in the reverse direction by the use 25 of spur gearing instead of chain gearing as also the elimination of the eccentric shaft altogether and placing the eccentrics on the crank shaft will occur to anyone familiar with this class of machinery.

30 Since at any time either of the two ducts 68 and 69 may have to act as the low pressure duct, it becomes necessary to connect the replenishing and back pressure pump to both ducts and to so arrange the connection 35 that the discharge from the pump will automatically shift from one to the other as occasion requires. Fig. 14 shows the pump with two discharge orifices 70 and 71 and Fig. 13 shows the manner of connecting 40 these orifices with ducts 68 and 69 through the circulating pipes 4 and 5 respectively. As parallel branches of a single discharge, the two passages 70 and 71 Fig. 14 are fitted with check valves 72 and 73 which open in 45 the direction of the discharge flow. The valves are arranged in axial alinement with each other and so that which ever valve is held shut by high pressure in its associated duct that valve will, by contact with the other 50 valve, hold the other valve open. Thus there will be the same freedom of communication between the governing piston 56 and the low pressure duct that there is in Fig. 12 where the low pressure duct is always the 55 same.

For relieving excessive pressure in the fluid connections a safety valve is required which, like the replenishing pump, will function automatically when there is a reversal in the functions of the high and low pressure ducts. Fig. 15 shows a valve which fulfils this requirement and which serves also as a manually controllable by-pass. The valve is placed as a cross connection 60 between the circulating pipes 4 and 5, T's

inserted in the latter communicating with the flanged connections on the valve body 74 and 76 and through these with two interior annular ports 77 and 78. Piston valve 79 is balanced with respect to pressures in both 70 ports. It also closes both ports at all times with respect to the region 80 comprising the interior of the piston valve and the two ends of the valve body. In its normal or closed condition Fig. 15, valve 79 shuts off ports 75 77 and 78 with respect to each other. From each of the connections 74 and 76 a small passage leads past a ball check valve into the region 80 toward which the ball check valves open. If there is a difference of 80 pressure between the connections 74 and 76 the greater pressure will prevail throughout the region 80 since said greater pressure will hold shut the ball check valve in the passage leading to the other or low pressure 85 connection. The greater pressure acting in the region 80 will, with respect to the valve stem 81, result in an unbalanced force tending to push the valve stem outward and move the valve toward the open position 90 Fig. 16 which movement will relieve the high pressure by opening a communication between ports 77 and 78. The outer end of the valve stem is equipped with a spring and spring box (similar to the parts al- 95 ready described in connection with the combined safety and reversing valve) by which the valve, as a safety valve, is held shut and by means of which, as a manually controllable by-pass, the valve is opened or 100 closed as desired.

Fig. 16 shows the valve as having been opened by hand for a by-pass without regard to pressures, and perhaps as a means of disconnecting the motor from the pumping engine when the latter is standing idle. As a safety valve Fig. 16 would show the handle and spring box in the dotted position the movement of the valve having compressed the spring an amount equal to the 110 movement.

Fig. 17 shows one type of general arrangement of my invention which dispenses with the separate reversing valve. In this arrangement 82 is the reversing pumping engine Fig. 13, and 83 is the safety and by-pass valve Fig. 15 placed as a cross connection between the circulating pipes 4 and 5. The motor 2 is of a size or capacity such that, within its range of speeds there 120 is included the speed of the engine crank shaft. The propeller shaft 3 extends completely through the motor and presents a free end in close proximity to the end of the engine crank shaft and in axial alinement therewith. A clutch 84 of any type, but shown as a simple jaw clutch, is provided for coupling together the engine and propeller shafts. The object of this arrangement is to provide an extra resource in 130

case of breakdown and also to provide a direct and probably more efficient drive in cases where there is a predominating speed such as "full speed ahead". In operation 5 the revolutions of the motor are brought to somewhere near the revolutions of the engine by means of the variable speed gear. The clutch is then connected and the safety valve takes care of any lack of synchronism 10 between the direct drive and the variable speed drive. The by-pass is then set wide open to take care of the circulation through the motor, after which the stroke of the pump is reduced to zero thus stopping all 15 circulation between the pump and the by-pass. In order to reduce as much as possible the resistance to the motor circulation the connecting pipes between the by-pass and the motor are made very short or the 20 pipes may be eliminated altogether by incorporating the by-pass into the motor structure. It will of course be understood that in thus providing for direct drive from the engine crank shaft I have to sacrifice 25 certain advantages which the engine derived from combining it with the pump. There are cases however where an apparently trifling difference of efficiency in favor of the direct drive will justify making provision for it.

Fig. 18 shows a general arrangement differing from Fig. 17 primarily in the fact that the motor is of so much greater capacity that its range of speed does not include the speed of the engine, the maximum revolutions of the motor being in fact only a fraction of the revolutions of the engine. In this case the engine and motor shafts are geared together in a velocity ratio approximately equal to the said fraction and provision is made for sliding the gears out of engagement or for disconnecting one of the gears and allowing it to turn idly on its shaft. In Fig. 18 the gear 85 is keyed to the propeller shaft and the pinion 40 86 turns freely on the engine shaft when not coupled thereto by the friction clutch 87. The direct drive feature of Fig. 17 and the geared drive feature of Fig. 18 are evidently just as applicable to general arrangements, such as Fig. 1, where the pumping engine is of the Fig. 2 type.

I claim:

1. A power transmission comprising, a 55 pump, a motor adapted to be operated by fluid under pressure, connections from said motor to the inlet and to the outlet of the pump, a safety valve arranged to be moved in one direction by any excessive pressure 60 occurring in one of said connections, and by such movement to establish a direct communication between them, a spring one end of which is operatively connected with said valve and tends to move it in the opposite

direction, and a valve-shifting member engaging the other end of said spring. 65

2. A power transmission comprising a pump, a motor adapted to be operated by fluid under pressure, connections from said motor to the inlet and to the outlet of the 70 pump, a reversing valve for governing the direction in which the fluid travels through the motor, a by-pass between said connections, and means, operating on said valve, for causing it to normally close said by- 75 pass yet allowing it to open the by-pass whenever an excessive pressure occurs in one of said connections.

3. A power transmission, comprising a pump, a motor adapted to be operated by 80 fluid under pressure, connections from said motor to the inlet and to the outlet of the pump, a receptacle adapted to contain a supply of fluid, and having at its lower portion a cylinder opening into the receptacle, 85 a replenishing pump having a piston arranged to work in said cylinder, one end of said piston being exposed to the interior of said receptacle, a suction connection from said receptacle to the replenishing pump at 90 the other end of said piston, a throttle valve controlling said suction connection, a delivery connection from the replenishing pump to that connection through which the operating fluid returns from the motor to the first-named pump, said throttle-valve having a surface exposed to the pressure of the fluid contained in said delivery connection, in such a manner that such pressure will tend to close the valve, and means acting in opposition to said pressure to keep the throttle valve open. 95

4. A power transmission comprising a pump, a motor adapted to be operated by 105 fluid under pressure, connections from said motor to the inlet and to the outlet of the pump, a receptacle adapted to contain a supply of fluid and having a cylinder opening into the receptacle, a replenishing pump 110 having a piston arranged to work in said cylinder, a suction connection from said receptacle to the replenishing pump at that end of the piston which faces away from said receptacle, a throttle valve controlling said suction connection, a delivery connection from the replenishing pump to that connection through which the operating fluid returns from the motor to the first-named pump, said throttle valve having a surface exposed to the pressure of the fluid 120 contained in said delivery connection, in such a manner that such pressure will tend to close the valve, and a spring tending to open the throttle valve against said pressure. 115

5. A power transmission comprising a pump, a motor adapted to be operated by fluid under pressure, connections from said 125

motor to the inlet and to the outlet of the pump, a receptacle adapted to contain a supply of fluid and having a cylinder opening into said receptacle, a replenishing pump having a piston arranged to work in said cylinder and to take fluid from said receptacle and to deliver such fluid under pressure to that connection through which the operating fluid returns from the motor to the first-named pump, and means for governing the action of the replenishing pump according to the pressure on the delivery side of said pump.

6. A power transmission comprising a pump, a motor adapted to be operated by fluid under pressure, connections from said motor to the inlet and to the outlet of the pump, a receptacle adapted to contain a supply of fluid and having a cylinder open to said receptacle, a replenishing pump having a piston arranged to work in said cylinder and to take fluid from said receptacle and to deliver such fluid under pressure to that connection through which the operating fluid returns from the motor to the first-named pump, and means for throttling the flow of fluid propelled by said replenishing pump in accordance with the pressure on the delivery side of said pump.

30 7. A power transmission comprising a pump, a motor adapted to be operated by fluid under pressure, connections from said motor to the inlet and to the outlet of the pump, a receptacle adapted to contain a supply of fluid, means for collecting leakage of the operating fluid and delivering it to said receptacle, a replenishing pump open to the lower portion of the receptacle and arranged to take fluid from said receptacle and to deliver it under pressure to that connection through which the operating fluid returns from the motor to the first-named pump, and means for governing the action of the replenishing pump according to the pressure on the delivery side of said pump.

8. A power transmission comprising a pump, a motor adapted to be operated by fluid under pressure, connections from said motor to the inlet and to the outlet of the pump, means for collecting leakage of the operating fluid, a replenishing pump having a piston one end of which is permanently exposed to the collected leakage, while the other end of the piston is arranged to take such collected leakage and to deliver it under pressure to that connection through which the operating fluid returns from the motor to the first-named pump, and means for governing the action of the replenishing pump according to the pressure on the delivery side of said pump.

9. A power transmission comprising an internal combustion engine having a plurality of driving members, a shaft having a

corresponding number of cranks, connecting rods each of which connects one of said driving members with one of the cranks, a pump-connecting rod pivoted to each driving member at the same axis as the crank connecting rod, a pump driven by each of said pump-connecting rods, and a motor arranged to be operated by the fluid propelled by said pumps.

10. A power transmission comprising an internal combustion engine having a plurality of driving members, a shaft having a corresponding number of cranks, connecting rods each of which connects one of said driving members with one of the cranks, a pump-connecting rod pivoted to each driving member at the same axis as the crank connecting rod, a lever connected with the other end of the pump-connecting rod, a pump driven by each of said levers, and a motor arranged to be operated by the fluid propelled by said pumps.

11. A power transmission comprising an internal combustion engine having a plurality of driving members, a shaft having a corresponding number of cranks, connecting rods each of which connects one of said driving members with one of the cranks, a pump-connecting rod pivoted to each driving member at the same axis as the crank connecting rod, a lever connected with the other end of the pump-connecting rod, an adjustable fulcrum for said lever, a pump driven by each of said levers, and a motor arranged to be operated by the fluid propelled by said pumps.

12. A power transmission comprising an internal combustion engine having a plurality of driving members, a shaft having a corresponding number of cranks, connecting rods each of which connects one of said driving members with one of the cranks, a pump-connecting rod pivoted to each driving member at the same axis as the crank-connecting rod, a lever connected with the other end of the pump-connecting rod, a fulcrum slide for each of said levers, a parallel motion connection between said slides, a pump driven by each of said levers, and a motor arranged to be operated by the fluid propelled by said pumps.

13. A power transmission comprising a plurality of operatively connected but differently timed driving members, levers actuated by said driving members, a fulcrum slide for each of said levers, a parallel motion connection between said slides, a pump driven by each of said levers, and a motor arranged to be operated by the fluid propelled by said pumps.

14. A power transmission comprising a plurality of operatively connected but differently timed driving members, levers actuated by said driving members, a pump oper-

- 10 relatively connected with each of the said levers, a fulcrum for each lever, adjustable to aline with the point at which the respective pump is connected with said lever, and to different distances from said point, means for adjusting the fulcrums in unison, a motor arranged to be driven by the fluid propelled by said pumps, and a device for reversing the motor, said device being so arranged relatively to the fulcrum-adjusting means that the latter will allow the reversing device to be operated only when the lever fulcrum alines with the pump connection.
- 15 15. A power transmission comprising a plurality of operatively connected but differently timed driving members, levers actuated by said members, a pump operatively connected with each of said levers, a fulcrum slide for each lever, adjustable to bring each fulcrum into line with the point at which the respective pump is connected with said lever, and to different distances from said point, means for adjusting said slides in unison, a motor arranged to be propelled by the fluid propelled by said pumps, a device for reversing the motor, and a projection connected with said slides and normally extending into the path of the reversing device to prevent its operation, but arranged to clear said path when the fulcrums are in line with the pump connections.
- 20 16. A power transmission comprising a pump, a motor adapted to be operated by fluid under pressure, connections from said motor to the inlet and to the outlet of the pump, a receptacle adapted to contain a supply of fluid, a replenishing pump comprising a cylinder permanently open to the lower portion of said receptacle, and a piston arranged to work in said cylinder and to take fluid from said receptacle and to deliver such fluid to that connection through which the operating fluid returns from the motor to the first-named pump.
- 25 17. A power transmission comprising a pump, a pocket for collecting leakage from the pump, a motor adapted to be operated by a fluid under pressure, connections through which the operating fluid will pass from the pump to the motor and return from the motor to the pump, means for collecting leakage from the motor and conveying such leakage to said pocket, a receptacle arranged to receive the overflow from said pocket, and a replenishing pump arranged to take fluid from said receptacle and to deliver such fluid under pressure to that connection through which the operating fluid returns from the motor to the first-named pump.
- 30 18. A power transmission comprising a pump, a motor adapted to be operated by fluid under pressure, connections from said motor to the inlet and to the outlet of the pump, a receptacle adapted to contain a supply of fluid, a replenishing pump comprising a cylinder both ends of which have connections to said receptacle, one of said connections being permanently open, a suction valve controlling the other connection, and a piston arranged to work in said cylinder and to take fluid from said receptacle and to deliver such fluid to that connection through which the operating fluid returns from the motor to the first-named pump.
- 35 19. A power transmission comprising a pump, a motor adapted to be operated by fluid under pressure, connections from said motor to the inlet and to the outlet of the pump, a receptacle adapted to contain a supply of fluid, an upright cylinder whose upper end is open to said receptacle, a suction connection from the lower end of said receptacle to the lower portion of said cylinder, and a replenishing piston arranged to work in said cylinder and to take fluid from said receptacle and to deliver such fluid to that connection through which the operating fluid returns from the motor to the first-named pump.
- 40 20. A power transmission comprising a pump, a motor adapted to be operated by fluid under pressure, connections from said motor to the inlet and to the outlet of the pump, a receptacle adapted to contain a supply of fluid, a replenishing pump located at, and communicating with, the lower portion of the receptacle so as to be below the level of the fluid in said receptacle, a suction connection from said receptacle to the replenishing pump, and a delivery connection from the replenishing pump to that connection through which the operating fluid returns from the motor to the first-named pump.
- 45 21. In testimony whereof I have signed this specification in the presence of two subscribing witnesses.

HARVEY D. WILLIAMS.
